UNITED STATES PATENT OFFICE.

JOSEPH H. POPE, OF HAMILTON, MASSACHUSETTS, ASSIGNOR TO UNITED SHOE MACHINERY COMPANY, OF BOSTON, MASSACHUSETTS, A CORPORATION OF NEW JERSEY.

NAILING MACHINE.

1,072,986.

Specification of Letters Patent.

Patented Sept. 9, 1913.

Application filed January 12, 1911. Serial No. 602,207.

To all whom it may concern:

Be it known that I, JOSEPH H. POPE, a citizen of the United States, residing at Hamilton, in the county of Essex and State of Massachusetts, have invented certain Improvements in Nailing Machines, of which the following description, in connection with the accompanying drawings, is a specification, like reference characters on the 10 drawings indicating like parts in the several figures.

This invention relates to machines for operating upon the heels of boots and shoes, and, while it relates more particularly to 15 machines for inserting attaching nails by which to secure the latter to shoes, some of its features may be embodied with good advantage in machines for pricking heels preparatory to the insertion of such nails.

20 It is an object of the invention to provide a machine of the general character above suggested which shall be of an improved and simplified construction and shall operate with accuracy to perform the operations 25 requisite for inserting nails inclined with respect to the surface of the heel which they first enter.

In many classes of work it is found advantageous to drive the attaching nails inclined longitudinally of the heel from the tread surface to the heel seat surface as in this way the heels may be secured more firmly than when the nails are driven perpendicularly. This is particularly true in 35 dealing with tapering heels or those undercut at the breast. Attaching nails driven perpendicularly to the tread face of such heels would leave the rear portion of the heel seat lift unsecured, and would be likely 40 to pass so close to its forward edge as to interfere with the subsequent breasting operation.

With a view to simplifying machines heretofore used in this class of work an important feature of the invention consists in 45 providing heel pressing members relatively movable in a direction substantially at right angles to the work engaging face of one member, together with a head movable in the same direction and carrying awls or drivers arranged to move in an inclined path when operating upon the heel held under pressure. In the machine herein disclosed this result is obtained by mounting 50 a driver block to slide transversely in ways

formed in the movable head and providing inclined driver passages in one of the heel pressing members through which the inclined drivers are arranged to work. As the drivers traverse the guiding passages 60 the driver block is left free to slide transversely on the head permitting the drivers to follow the path determined by the passages.

The present invention may be utilized 65 with particularly good results in a machine having a multiple gang of inclined drivers arranged to form several horse-shoe-shaped nailings of different sizes. In such construction the increased number of inclined 70 drivers renders the transverse movement of the driver block substantially positive and eliminates the tendency to bend which may appear where drivers of less number are employed. This tendency to bend is caused 75 by the frictional resistance to transverse movement of the driver block. It will be understood that in practice only one horse-shoe-shaped nailing in the die plate is loaded with nails and that those drivers which 80 do not encounter nails in the driver passage are equally as effective in producing the transverse movement of the driver plate as those which are also effective in driving.

The driver passages may have a substantially uniform inclination or, if it is desired to drive some of the attaching nails with an outward as well as rearward inclination, the corresponding driver passages may be made to diverge laterally, the drivers being 85 permitted to deflect laterally to follow these 90 passages by reason of their resiliency.

An important feature of the invention, accordingly, consists in the combination, with a heel pressing member having inclined and divergent driver passages, of a driver block free to move transversely during the attaching operation and drivers free to spring or bend laterally.

In those constructions where it is necessary to draw the drivers out of the guiding passages to permit attaching nails to be supplied to the passages it is important to control the path of the drivers until their ends have been again entered in the guiding 105 passages.

To this end another feature of the invention consists in providing guiding means for controlling the position of the driver block and drivers upon the head when it 110

has moved sufficiently from the work pressing members to carry the ends of the drivers out of the passages, said means being arranged to release the driver block and leave the drivers free to follow the path of the passages when the head has again moved sufficiently to enter the ends of the drivers in the passages. In the machine herein disclosed the driver block is carried by a plate having an aperture slidably fitted to a stationary guide pin which terminates at a distance from the ends of the guiding passages substantially equal to the length of the drivers. Preferably the guide pin is removably mounted in a stationary bracket so that when it is desired to remove the driver block from the head it may be conveniently released by sliding the guide pin out of engagement with the plate.

For purposes of illustration the present invention will be described as embodied in a nailing machine of the type shown in my prior Patent No. 446,885 to which reference may be had for further details of construction, although it is to be understood that the invention is not limited to this type of heel nailing machine but is of general application.

In the accompanying drawings, — Figure 1 is a rear view in perspective of a preferred embodiment of the invention; Fig. 2 is a sectional view of the operative parts of the machine showing the position of the drivers at the end of the driving stroke, and Fig. 3 is a sectional view at right angles to that of Fig. 2, showing the drivers retracted.

The transversely extending bar 12, which constitutes the die plate is rigidly attached to part of the frame of the machine, and is provided with a multiplicity of driver passages having a substantially uniform inclination toward the rear of the machine. The cross head 14 is secured to and actuated by the side rods 16 to which a vertical reciprocation is imparted by any suitable mechanism. On its lower side the cross head is provided with a square projecting portion to which is rigidly attached a block 20 provided with oppositely disposed ribs which form a horizontal guideway. Slidingly mounted in said guideway is a plate 22 carrying on its lower surface the driver block 24. In the driver block are mounted a number of drivers, one for each of the driver guiding passages in die plate 12. The drivers are set in the driver block at a longitudinal inclination corresponding to that of the driver passages 13. The drivers and passages are arranged to form a number of different sized horse shoe shaped nailings, the machine being adapted to attach heels of different sizes by supplying attaching nails to one or another of the series of driver passages.

Suitable means are provided for guiding

the drivers in a vertical path while they move toward or from the driver passages in order that the ends of the drivers may be properly located to enter the ends of the driver passages when the cross head moves downwardly. In the machine herein disclosed the plate 22 is provided with a rearwardly extending ear 30 which is apertured to slide upon a vertical guide pin 32, the latter being removably mounted in a socket 34 formed integral with a stationary bracket 36. The bracket has a pair of enlarged ends 37 which are bored to permit the passage of the side rods 16, and are rigidly secured to sleeves 39 constituting bushings through which the rods 16 reciprocate. The guide pin 32 is provided with a collar 33 which rests on top of the socket 34. The collar 33 is adjustably secured to the guide pin 32 by a set screw; the pin is held in the socket by a set screw or other convenient means and is tapered at its lower end in order to enter more readily the aperture in the ear 30 and center the carrying plate 22 when the cross head is elevated. When it is desired to remove the driver block from the head 14 for any reason the pin 32 may be loosened and drawn upwardly in its socket until it disengages the ear 30 whereupon the plate 22 and driver block are free to be drawn out of the guideways in the block 20. The vertical position of the guide pin is gaged by the collar 33, the latter being so set as to hold the end of the pin above the surface of the die plate a distance equal to the length of the particular drivers being used.

Below the die plate 12 is mounted a jack 40, upon which the shoe to be heeled is placed. The jack may be moved out of alignment with the cross head to permit a shoe to be jacked, as is common in machines of this kind. The jack is also movable vertically toward and from the die plate 12 in order that the heel to be attached may be subjected to pressure preliminarily to the nail driving operation. Any suitable mechanism may be utilized to effect the vertical movement of the jack, a preferred construction being disclosed in my prior patent above identified. Side clamps 42 are provided for properly positioning the shoe upon the jack.

If it is desired to cause some of the attaching nails to diverge as they are driven, as would be the case should the heels to be attached be tapered or undercut at the sides, the outer driver passages 13' are made to diverge downwardly, as shown in Fig. 3, in addition to their rearward inclination. The corresponding drivers in traversing the divergent passages spring or bend outwardly as suggested by the dotted line position of the driver 26' in Fig. 3. On being withdrawn from the passage, however, these drivers reassume their normal position by

reason of their resiliency and stand substantially parallel with the others.

In operating the machine, the shoe is jacked and positioned with the heel blank in place under the die plate 12, attaching 5 nails are then inserted in the proper series of driver passages and power is applied to the machine. The jack is thereupon forced upwardly putting the work under pressure 10 and the cross head 14 is moved downwardly. As the cross head descends the apertured ear of the carrying plate 22 slides downwardly upon the pin 32, thus guiding the driver block and drivers in a vertical path. 15 When the cross head has moved sufficiently to enter the ends of the drivers in the driver passages the ear 30 has moved below the end of the guide pin releasing the driver block so that the advancing drivers are 20 free to follow the path determined by the driver passages. On the continued downward movement of the cross head the drivers and driver block are bodily shifted toward the rear of the machine as a result of 25 the co-action of the inclined drivers and the inclined passages, the resultant movement being in a path parallel to the direction of the driver passages and the attaching nails are driven from the passages into the heel blank and sole in the same direction, being 30 clenched toward the rear of the shoe upon the surface of the jack. On the upward movement of the cross head the driver passages shift the drivers and driver block forwardly so that by the time the plate 22 35 has been raised to the elevation of the lower end of the guide pin 32, the aperture in the ear 30 has been moved into alignment with the tapered end of the pin and effective 40 connection is again established.

The invention has been herein disclosed as embodied in a heel nailing machine but it is within the scope of the invention to substitute awls for the drivers shown or otherwise 45 modify the construction specifically described to adapt the machine for pricking heels instead of inserting and driving attaching nails.

Having described my invention what I 50 claim as new and desire to secure by Letters Patent of the United States is:—

1. A heelng machine having, in combination, a plate provided with a heel engaging face and a plurality of guiding passages extending at an inclination to said face, a full 55 gang of tools for operating on a heel movable into and out of said passages, means for guiding said tools in a path inclined with respect to the guiding passages to cause 60 them to enter said guiding passages, said means being constructed and arranged to permit said tools to move out of operative relation thereto on entering the guiding 65 passages so that the passages may control the path of the tools.

2. A heelng machine having, in combination, a plate provided with a heel engaging face and a plurality of guiding passages extending at an inclination to said face, a full gang of tools for operating on a heel mounted obliquely and parallel with the guiding passages in said plate, said tools being movable into and out of said passages, and means for guiding said tools for movement in a vertical path while out of said 70 passages, said means being constructed and arranged to permit the tools to move out of operative relation thereto on entering the guiding passages, whereby they may be guided in an oblique path by the guiding 75 passages. 80

3. A machine of the class described having, in combination, a multiple die block having inclined driver passages arranged to form several sizes of horse shoe shaped 85 nailings, a driver block carrying drivers correspondingly arranged and disposed at similar inclinations, actuating means for moving the drivers out of said passages to permit the insertion of nails and into said 90 passages to drive the same, and guiding means arranged for controlling the drivers while out of said driver passages, said means being so constructed as to release 95 said drivers when they enter said passages, the drivers being thereafter guided in an inclined path by the driver passages alone. 100

4. A machine of the class described having, in combination, a cross head mounted for vertical reciprocation, a driver block carried thereby and movable transversely thereon, a plurality of drivers arranged in the form of a horse shoe on said driver block and all disposed at an inclination to the path of the cross head, a die block having inclined driver passages, a guiding device for said drivers terminating at a distance from said die block approximately equal to the length of the drivers whereby 105 the drivers are freely permitted to follow the passages after they have entered the same. 110

5. A machine of the class described, having, in combination, reciprocating side rods and a cross head carried thereby, a driver block and inclined drivers movable transversely on said cross head, a die block having inclined passages, a bracket extending between said side rods having a socket therein, and a guide pin projecting vertically from said socket and having a sliding connection with said driver block, said pin terminating a distance from the die block approximately equal to the length of the drivers. 115 120

6. A machine of the class described having, in combination, reciprocating side rods and a cross head movable therewith, a driver block and inclined drivers movable transversely with respect to the cross head, 125 130

4
a die block disposed in the path of said cross head having inclined passages extending parallel with said drivers, a bracket having apertures through which said side rods pass, 5 said bracket extending rearwardly with respect to the side rods, then upwardly and laterally, and a guiding device for the driver block carried by said bracket.

7. A machine of the class described having, in combination, a work support, a head movable vertically toward and from said support, a multiple gang of inclined drivers carried by the head and arranged to form several horse-shoe-shaped nailings of different sizes, all of said inclined drivers being movable transversely upon the head, means for preventing such transverse movement during a part of the movement of the head, and a die block having a multiple series of 15 guiding passages all inclined in the same general direction to the face of the die block for guiding the drivers in inclined paths during another part of the movement of said head.

25 8. A heel nailing machine having, in combination, a work support, a head arranged for reciprocation toward and from said support, a driver block mounted upon the head for transverse movement, a multiple gang 30 of inclined drivers set in the driver block in the form of several horse-shoe-shaped nailings of different sizes, and a die block having correspondingly inclined driver passages, the driver block being controlled in 35 its transverse movement on the head by the co-action of the inclined drivers and the inclined passages, there being a greater number of such drivers and passages than the number of nails to be driven.

40 9. A machine for operating upon heels having, in combination, a work support, a head movable toward and from the work support, a tool block transversely movable in the head, a gang of tools set in the tool 45 block in parallel relation and all inclined relatively to the path of movement of the head, and a die block having tool passages all inclined in the same general direction to the face of the die block, the transverse position of the tool block in the head being controlled, during the reciprocation of the tools in the die block, by co-action of the inclined tools and the inclined passages, the tool block being otherwise freely movable in the 50 head.

55 10. A machine of the class described having, in combination, heel pressing members relatively movable in a vertical direction, one of said members having inclined driver

passages, a vertically movable head, a driver 60 block transversely movable in said head and inclined drivers rigidly mounted therein, and guiding means constructed and arranged to control the driver block while the drivers are out of said driver passages and leave the 65 driver block freely movable in said head while the drivers are working in said passages.

11. A machine of the class described having, in combination, a reciprocatory head 70 carrying a transversely movable driver block, a multiple gang of resilient drivers mounted in said block in the form of several horse-shoe-shaped nailings, and work pressing members, one of which has a multiple 75 series of inclined and laterally divergent driver passages, said drivers being permitted to follow the inclination of said passages by the transverse movement of the driver block and to diverge laterally by reason of their 80 resiliency, there being a greater number of inclined drivers and passages than the number of nails to be driven.

12. A machine of the class described having, in combination, a work support, a head 85 arranged for reciprocation toward and from the support and carrying a transversely movable driver block, inclined drivers on the block, a die plate perforated to receive the drivers, and a guide pin for controlling the 90 transverse position of the driver block terminating at a distance from the die plate approximately equal to the length of the drivers and having provision for adjustment whereby drivers of different lengths may be 95 accommodated.

13. A machine for operating on heels having, in combination, a work support, a head movable toward and from the work support, a tool block mounted in the head and having 100 a gang of tools all disposed at substantially uniform inclination to the path of movement of the head, and a die plate with correspondingly inclined tool passages for the tools, the tool block being constrained to 105 move in the direction of movement of the head during one part of its stroke and being arranged for free movement transversely of the path of the head by the co-action of the inclined tools in the inclined passages during 110 another part of its stroke.

In testimony whereof I have signed my name to this specification in the presence of two subscribing witnesses.

JOSEPH H. POPE.
